UNITED STATES PATENT OFFICE.

SAMUEL A. MEYERS AND CHARLES F. PARKER, OF SAN FRANCISCO, CALIFORNIA.

ELECTRIC SWITCH.

1,333,762.

Specification of Letters Patent. Patented Mar. 16, 1920.

Application filed April 2, 1917. Serial No. 159,368.

To all whom it may concern:

Be it known that we, SAMUEL A. MEYERS, a subject of Russia, and CHARLES F. PARKER, a citizen of the United States, residing 5 at San Francisco, in the county of San Francisco, State of California, have invented a new and useful Electric Switch, of which the following is a specification, in such full and clear terms as will enable 10 those skilled in the art to construct and use the same.

This invention relates to an electric switch, an object of the invention being to provide a switch which will have its live 15 terminals so protected that a person cannot accidentally place the fingers upon said terminals.

Another object of the invention is to provide a switch which will have the connecting 20 blades entirely removed from the terminals so that they will not be in any way connected therewith when the switch is open.

Another object of the invention is to provide an inclosure for the switch which will 25 prevent it from being tampered with when in use and which may be locked with an ordinary padlock either in the open or the closed position of the inclosure as may be desired.

30 Other objects of the invention will appear as the description proceeds.

An embodiment of the invention is shown in the drawings in which the same reference numeral is applied to the same portion 35 throughout, but we are aware that there may be modifications thereof.

Figure 1 is a plan view of the switch with the cover open and the terminal guard removed therefrom for the purpose of illustration.

40 Fig. 2 is a plan view of the switch on a slightly larger scale than Fig. 1, showing the terminal guard in place, and the cover partly broken away.

45 Fig. 3 is a view of the switch looking from the left of Fig. 1 in edge elevation, the switch box being in section and a portion of the cover being broken away for the purpose of illustration.

50 The numeral 1 represents a shallow box having an ear at 2 with a hole to receive the hasp of a padlock. A hinge at 3 connects the box 1 with the cover 4, said cover having a lug projecting at 5, which lug is provided 55 with a hole which registers with the hole in the lug 2 when the cover is closed. Within

the box is mounted a well known form of double pole switch carried by a block 6. The block 6 is suitably connected to the box with screws 7 and 8 and it has inlet contact 60 points 9 and 10 to which the inlet wires 11 and 12 are connected in a well known manner.

Outlet contacts 13 and 14 are provided, which are suitably connected to the fuses 65 15 and 16. Placed over the top of the two terminals 9 and 10 is a sheet of insulating fiber 17, the sides of which are turned down as indicated at 18 to rest on the bottom of the box at each side while the upper edge 70 thereof is turned upwardly as indicated at 19 in order that it may be connected with the box by means of the screws 20 and 21. This fiber cover has two slots 22 and 23 75 therein to allow the knife contact blades 24 and 25 (which are suitably secured to an insulating block 26 carried by the cover 4) to pass through when the cover is closed, and when said cover is closed the terminals 9 and 13 and 10 and 14 are connected together.

On the upper portion of the box there is a hole 28, the object being to provide means whereby the padlock 29 may be used to lock the switch and cover open if desired, 85 since when the padlock is inserted in said hole 28 it will be impossible to close the cover because the cover fits the base snugly and cannot pass over any enlargement such as the hasp of the padlock. When the 90 switch is closed, the padlock may be inserted through the holes in the two lugs 2 and 5, and the switch cannot be tampered with until the person who has the key removes the padlock.

95 In order to hold the cover shut without the necessity of locking it, a spring 30 is fastened within the lower end of the box, and it has a knob 31 connected thereto which is adapted to release the spring from the 100 cover when it engages the hole 32. The switch block is of common porcelain type having holes for the screws 7 and 8, a depression 33 and a slot 34 to receive a securing screw 35.

105 Having thus described our invention, what we claim as new and desire to secure by Letters Patent of the United States, is as follows, express reservation being made of permissible modifications.

110 An electric switch comprising a block carrying a plurality of switch points, a box

around the switch points and block, a slotted guard having two edges turned down to space it away from the switch points and covering two of the switch points, said guard 5 also having a flange for securing it to the box, a cover hinged to the box and a knife switch carried thereby and adapted to project through the slots of the insulated guard

for connecting the terminals with the circuit.

In testimony whereof we have hereunto set our hands this 22nd day of March A. D. 1917.

SAMUEL A. MEYERS.
CHARLES F. PARKER.
